UNITED STATES PATENT OFFICE.

CLEMENT A. DUNBAR, OF DETROIT, MICHIGAN.

LEER FOR ANNEALING GLASSWARE.

SPECIFICATION forming part of Letters Patent No. 759,165, dated May 3, 1904.

Application filed January 14, 1902. Serial No. 89,708. (No model.)

To all whom it may concern:

Be it known that I, CLEMENT A. DUNBAR, a citizen of the United States, residing at Detroit, in the county of Wayne and State of Michigan, have invented certain new and useful Improvements in Leers for Annealing Glassware, of which the following is a specification, reference being had therein to the accompanying drawings.

10 The invention relates to feeding mechanism for leers; and it consists in devices for feeding glass articles from the outside of the leer into a carrier which travels through the leer, and, further, in the construction of a reciprocating device comprising a glass-holder which receives the article, delivers it into the leer, and then releases it and withdraws therefrom, and in which the construction, combination, and arrangement of the various parts is hereinafter described, and particularly pointed out in the claims.

15 In the drawings, Figure 1 is a vertical central section through a leer, showing my feeding-in mechanism in elevation and with a push-off in section. Fig. 2 is a perspective view of the feeding-in device and the push-off, showing the holder in position to receive the glass article. Fig. 3 is a front elevation thereof, showing the holder in position to deposit the article in the leer. Fig. 4 is a side elevation of the upper part of Fig. 2. Fig. 5 is a section through the push-off, showing the holder in position to receive the glass article.

20 My feeding-in device is shown in connection with a horizontal leer formed of a horizontal tunnel or brickwork, of which 26 is the roof. At each end of the tunnel is a well 38, in which are transverse shafts 41, carrying sprocket-wheels 40, over which runs an end-less carrier 45, comprising a series of pans or plates upon which the articles are to be placed. The carrier runs intermediate the wheels upon guideways 35 and 36, being provided with suitable wheels 49, which rest upon the guides 45 in the leer. In the roof of the tunnel is a recess 52, in which is a gas-burner 53, having the jets so as to direct the flame through the leer and produce a slow traveling forward movement of the heat from the inlet to the outlet

end, either without the use of a stack or 50 through draft-producing devices. The inlet end of the leer is closed by a wall 43. At the outlet end is a detachable cover 56, which when removed exposes the end of the carrier, from which the articles may be removed in 55 any suitable manner.

The particular construction of the leer I do not herein claim as I have made that the subject-matter of another application previously filed.

60 In the roof of the leer is a feed-opening 25, and extending up from this is a casing 21, forming the well from the floor above to the leer.

65 In making tumblers, particularly pressed tumblers which come from the press before they are perfectly set or hardened, it is desirable to shape the bottom, and as they are taken from the press they are set upon a seat or table 2 beside the carrying-in device, the 70 concave bottom of the tumbler resting upon a movable head 3, which is connected to the actuating-arm 4, pivoted in a bracket 5 upon a table or frame 6. The lever 4 has a suitable handle and an actuating-arm 7, which is 75 connected to the pusher 8. Lifting upon the hand-lever 4 moves the pusher 8 laterally and at the same time withdraws the head 3 and pushes the tumbler (marked 9) from its support into the two-part socket or holder 10. 80 Each half of this socket is supported upon a vertical lever 11, these levers being pivoted upon the sliding head 12, having the guides 13, which slide upon the vertical guide-bar 14. The upper end of the levers 11 have the 85 inclines 15, between which engages the pin 16 on the bracket 17, secured to the tripper-bar 18. These levers are held in their upper position with the inclines 15 in contact with the pin 16 by means of a counterweight 29, connected by a suitable rope or chain with the upper end of the head 12, as plainly shown in Fig. 1. When the article is pushed into the cup or receiving-socket 10, the head 12 is lowered by a suitable mechanism. I have shown 90 an endless chain 19 in Fig. 1 with a finger 20 projecting into the path of the lower guide 13 of the head, so that as the chain is moved it

will move the head downward, lifting the counterweight 29 and lowering the cup or receiving-socket 10 through the well 21, arranged over the aperture 25 in the top of the leer-tunnel 26. When the socket 10, with its glass article, reaches its lowest point, the tripper-bar 18 strikes the stationary stop or bracket 27, and the head continues its downward movement a short distance, while the tripper-bar remains stationary. This lowers the levers 11 in relation to the pin 16 and also in relation to the pins 28 on the bracket 17 and which contact the outer faces of the inclines 15. This movement turns the levers 11 about their pivots, causing the lower ends to separate, as shown in Fig. 3, and to open the receiving socket or cup 10 and permit the article therein to descend by gravity and be deposited upon the pan of the leer, as illustrated in Fig. 3. By any suitable mechanism (not shown) the chain 19 may now be given a reverse movement, raising the finger 20 and allowing the counterweight to raise the head 12 with its levers. When it reaches near the top of its movement, the tripper-bar 18 strikes the stop or bracket 30 and rocks the levers 11 about their pivots, closing the receiving-cup, as shown in Fig. 2.

I preferably arrange a series of these feeding-in devices side by side, so that the operator may feed the articles to them successively, and thus have a continual feed for the articles into the leer. Any suitable mechanism (not shown) may be arranged for causing them to act successively or together, as desired.

Heretofore it has been the usual practice to pile the glassware as it comes from the press upon pans and to shove the pan into the end of the leer, which was continually open, and then by a hand-lever remove the carrier a distance of a pan, and thus to gradually move the material from one end of the leer to the other. So far as I am aware no devices have been heretofore used for feeding the glassware upon the carrier which is traveling through the leer, in this case the carrier being actuated continuously by any suitable mechanism. (Not shown.) So far as I know I am also the first to feed a leer by mechanism through the roof thereof upon an endless carrier, as herein shown.

What I claim as my invention is—

1. In a machine of the character described, the combination of a carrier, of a feeding device for hollow glass articles comprising reciprocating devices, including a several-part socket for the reception of the articles, and

means for causing the parts of said socket to approach or recede. 60

2. In a machine of the character described, the combination with a carrier, of a sectional holder comprising a several-part socket for hollow glass articles, means for reciprocating said holder to and from the carrier and for opening the socket to deposit the articles upon the carrier and for maintaining the socket in its closed condition during the feeding movement. 65

3. In combination with a carrier, a reciprocating head, levers pivoted thereto, a sectional holder at the end of the levers, means for holding the sections together during the feeding movement, and automatic means for opening the holders to deposit the article upon the carrier. 70

4. The combination with a reciprocating head, of the levers 11 pivoted thereto and having sectional holders at the lower ends thereof, and inclines 15 at the upper ends of the same, and the actuating-pins 16 and 28 coacting with said upper ends. 80

5. The combination with a reciprocating feeding device, of a table 2, the lever 4 pivoted thereto, the head 3 movably connected with the lever and projecting through the table, and a pusher 8 actuated by the lever. 85

6. In combination with a leer having an opening in one wall thereof, a traveling carrier in said leer a portion of which is in adjacency to said opening, and a device arranged to be projected into and withdrawn from said opening to deposit the glassware upon the carrier. 90

7. In combination with a leer having an opening in its top wall, a traveling carrier in said leer a portion of which is at all times below said opening, and a device arranged to shift in a substantially vertical plane into and out of said opening to deposit the glassware upon the carrier. 100

8. In combination with a leer having an opening in its top wall, a horizontally-disposed traveling carrier in said leer a portion of which is adapted to register with said opening, and a vertically-reciprocatory device arranged to be projected into and withdrawn from said opening to deposit the glassware upon the carrier. 105

In testimony whereof I affix my signature in presence of two witnesses.

CLEMENT A. DUNBAR.
